US00D868609S

(12) **United States Design Patent** (10) **Patent No.:** **US D868,609 S**
(45) **Date of Patent:** **** Dec. 3, 2019**

(54) **CONTACT SENSOR**

(71) Applicant: **Hangzhou Great Star Industrial Co., Ltd.**, Hangzhou (CN)

(72) Inventor: **Weiyi Wang**, Hangzhou (CN)

(73) Assignee: **Hangzhou Great Star Industrial Co., Ltd.**, Hangzhou (CN)

(**) Term: **15 Years**

(21) Appl. No.: **29/662,924**

(22) Filed: **Sep. 10, 2018**

(30) **Foreign Application Priority Data**

Mar. 23, 2018 (CN) 2018 3 0111034

(51) **LOC (12) Cl.** **10-05**

(57)

CLAIM

The ornamental design for a contact sensor, as shown.

DESCRIPTION

FIG. 1 is a perspective view of the contact sensor showing my new design;

FIG. 2 is a front view of the contact sensor depicted in FIG. 1;

FIG. 3 is a rear view of the contact sensor depicted in FIG. 1;

FIG. 4 is a left side view of the contact sensor depicted in FIG. 1;

FIG. 5 is a right side view of the contact sensor depicted in FIG. 1;

FIG. 6 is a top view of the contact sensor depicted in FIG. 1; and,

FIG. 7 is a bottom view of the contact sensor depicted in FIG. 1.

1 Claim, 4 Drawing Sheets
